CLAIM

The ornamental design for a linear LED light, as shown and described.

DESCRIPTION

FIG. 1 is a front, top and right side perspective view of a linear LED light, showing our new design;
FIG. 2 is a front view thereof;
FIG. 3 is a rear view thereof;
FIG. 4 is a left side view thereof;
FIG. 5 is a right side view thereof;
FIG. 6 is an enlarged top plan view thereof;
FIG. 7 is an enlarged bottom plan view thereof;
FIG. 8 is an enlarged view of portion 8 shown in FIG. 1; and,
FIG. 9 is an enlarged view of portion 9 shown in FIG. 1. The broken lines shown in the drawings depict portions of the linear LED light that form no part of the claimed design. Additionally, the dot-dash broken line rectangles in FIG. 1 indicate portions of the design that are enlarged to show detail in FIGS. 8 and 9; the dot-dash broken line rectangles form no part of the claimed design.
